[57] **CLAIM**

The ornamental design for a decorative panel for a gable of a building, as shown and described.

DESCRIPTION

FIG. 1 is a front elevational view of a decorative panel for a gable of a building, the rear of said panel being plain and unornamented;

FIG. 2 is a side elevational view thereof;

FIG. 3 is a top plan view thereof; and,

FIG. 4 is a bottom plan view thereof.

FIG. 1

FIG. 3

FIG. 4

FIG. 2
